(57) **CLAIM**

The ornamental design for a lever for a toaster, as shown and described.

DESCRIPTION

FIG. 1 is an isometric view of a lever for a toaster according to the present invention;

FIG. 2 is a front elevation view of the lever of FIG. 1;

FIG. 3 is left side elevation view of the lever of FIG. 1;

FIG. 4 is a top plan view of the lever of FIG. 1; and,

FIG. 5 is a bottom plan view of the lever of FIG. 1.

The right side elevation view of the lever is a mirror image of the left side elevation view shown in FIG. 3, and is therefore not shown.

The broken lines in the Drawings are for illustrative purposes only in order to show the environment in which the design is associated and form no part of the claimed design.
